(57) **CLAIM**

The ornamental design for a food canister, as shown and described.

DESCRIPTION

1.1—front view of a food canister showing my new design;

1.2—back view thereof;

1.3—left view thereof;

1.4—right view thereof;

1.5—top view thereof;

1.6—bottom view thereof; and

1.7—perspective view thereof.

The broken lines shown in the figures depict portions of the food canister that form no part of the claimed design.

1 Claim, 7 Drawing Sheets
